UNITED STATES PATENT OFFICE.

DAVID P. THOMSON AND HENRY GEISENHÖNER, OF SCHENECTADY, NEW YORK, ASSIGNORS TO THE GENERAL ELECTRIC COMPANY, OF NEW YORK.

FIELD-MAGNET STRUCTURE.

SPECIFICATION forming part of Letters Patent No. 571,462, dated November 17, 1896.

Application filed August 18, 1896. Serial No. 608,150. (No model.)

To all whom it may concern:

Be it known that we, DAVID P. THOMSON and HENRY GEISENHÖNER, citizens of the United States, residing at Schenectady, in the county of Schenectady, State of New York, have invented certain new and useful Improvements in Field-Magnet Structures, (Case No. 388,) of which the following is a specification.

10 Our invention relates to the field-magnets of dynamo-electric machines, and particularly to those in which the field-magnet revolves and the armature remains stationary. Most of the examples of this type of machine are 15 of the alternating-current type, in which it is necessary for efficiency to employ a laminated field-magnet structure. At the same time the pole-tips for the best effect should be expanded, so that (among other reasons) 20 the magnetic density need not be forced unusually high in the air-gap by reason of the smallness of the pole-face through which the lines are projected. The pole-tip itself should also be laminated. With this construction 25 it has been found difficult to devise sufficient means for rendering the field-magnet coils removable. It has been proposed to have a cast inner structure, to which the laminated field-magnet poles might be bolted in various ways; 30 but this is for some reasons objectionable, occasioning a dissimilarity in the material in the magnetic circuit which is undesirable and rendering the connecting means between the pole and the central structure difficult of access. Solid poles secured in the same way 35 have also been used, but this is objectionable for the same and other reasons.

The construction which we have devised consists in a laminated field-magnet structure 40 with salient poles having laminated pole-tips, the tips of the poles being removable, so that the field-magnet coil may be placed in position. To effect a secure junction and to reduce the reluctance of the magnetic circuit 45 to the lowest point, we arrange the laminæ of the pole-tip with interlocking projections and also have projections upon the laminæ forming the body of the pole. Insulated bolts clamp the laminæ together, the surfaces of 50 the laminæ also having a frictional engagement tending to assist the strength of the

bolts and render the structure exceedingly solid and compact and capable, when revolved at high speed, of resisting centrifugal and magnetic stresses.

55

It is manifest that the general type of our invention thus described may be much varied. We may, if so desired, intersperse the individual laminæ of the tip, having projections between the laminæ of the pole itself, or we 60 may arrange the pole-tip with a number of projecting laminæ in a group. The form and location of the projecting parts which make the connection between the pole-tip and the body of the pole may also be indefinitely varied.

65

The accompanying drawings show some of the forms which our invention may assume.

Figure 1 is a side elevation, partly in section and partly broken away, of a field-magnet embracing our construction. Fig. 2 is a partial section upon the line 2 2 of Fig. 1. Fig. 3 is a side elevation of a single pole-tip of modified form. Fig. 4 is a section on the line 4 4 of Fig. 3. Fig. 5 is a plan, and Fig. 70 75 6 a side elevation, of another modification. Figs. 7 and 8 are similar views of still another modification. Figs. 9 and 10 are side elevations of field-magnets assembled according to our invention, Fig. 9 showing a spider with 80 a rim and Fig. 10 a spider in which the arms are connected only by the laminæ.

In Fig. 1, A is the body of the field-magnet. B B are the pole-tips. The laminæ forming the body of the field-magnet have projecting 85 portions G, adapted to form interlocking surfaces with the laminæ of the pole-tip. In dotted lines at G' we show how the laminæ of the field-magnet structure may be reversed in position, so that with a single die the effect of 90 two locking projections upon each polar end may be produced. By reversing the position of the individual laminæ of the pole-tips B a similar effect may be produced. F is a field-magnet coil, one of which, of course, would be 95 provided for each of the salient poles. Bolts E are used to lock the laminæ in place after the pole-tip has been placed over the field-magnet coil, and similar bolts E' E' are employed to assemble the pole-tip before it is 100 put in place.

In Fig. 2 the same construction is shown,

only one of the bolts being illustrated, and the interleaving of the laminæ forming interlocking surfaces is illustrated.

In Figs. 3 and 4 a modified form is shown. 5 Some of the laminæ of the pole-tip are of the size shown in full lines. Some of them are cut away, as shown in dotted lines, to correspond to the projecting ends of the poles. Similarly, some of the laminæ of the poles are 10 as shown in full lines and others have their ends projecting into a pole-tip, as shown in dotted lines. Preferably the laminæ alternate in position in groups, and this subdivision or alternation may be carried as far as 15 is desirable. As before, bolts E E lock the pole-tip in place.

In Figs. 5 and 6 we show another modified construction. In this case undercut or dovetailed projections are formed upon the polar 20 projection, and the pole-tip B is secured in place by keys I I'. This is not, however, the preferred form of our invention.

In Figs. 7 and 8 we show still another modification, in which the ends B' B' of the pole-tip are formed with dovetailed projections and the ends of the pole itself are formed with undercut grooves corresponding in form to the interlocking portions of the polar tips B' B'.

30 In Fig. 9 a spider K with a rim is shown, having the laminæ connected to it by dovetailed projections and having the polar tips of our invention.

Fig. 10 corresponds to Fig. 9, except that

the spider is rimless, the arms being disconnected, so that the structure may move slightly under changes of temperature. 35

What we claim as new, and desire to secure by Letters Patent of the United States, is—

1. A field-magnet structure for a dynamo- 40 electric machine, consisting of salient poles of laminated structure, provided with separate laminated tips, and means for securing the tips to the poles.

2. A field-magnet structure for a dynamo- 45 electric machine, comprising laminated salient poles provided with laminated expanded tips, some of the laminæ of the tip provided with tenons which register with suitable spaces in the laminæ of the pole, and means 50 for holding the parts in engagement.

3. A field-magnet structure for a dynamo- 55 electric machine, comprising laminated pole-pieces provided with laminated expanded tips or pole-faces, the laminæ of the pole and tip having engaging tenons and spaces, and arranged in groups, with means for securing the parts together, thus maintaining them in place by the strength of the securing means 60 and by their frictional engagement.

In witness whereof we have hereunto set our hands this 14th day of August, 1896.

DAVID P. THOMSON.
HENRY GEISENHÖNER.
